UNITED STATES PATENT OFFICE.

JAMES DANIEL JOYCE, OF PHILADELPHIA, PENNSYLVANIA.

WINDING MACHINE.

Application filed May 1, 1924. Serial No. 710,252.

To all whom it may concern:

Be it known that I, JAMES D. JOYCE, a citizen of the United States, residing at Philadelphia, in the county of Philadelphia and State of Pennsylvania, have invented certain new and useful Improvements in Winding Machines, of which the following is a specification.

This invention relates in general to winding machines for winding double taper ended cops or bobbins.

In winding machines of this type the taper of the end of the winding is governed by a shaper which controls the position of the contact or progression wheel, and hence of the thread guide carrier with relation to the spindle, during the early stages of the winding operation. When it is desired to wind a cop with a different taper it is necessary to replace this shaper with one having the desired pitch. Additionally such a shaper must be replaced by another when it is desired to use the machine to wind a cop or bobbin having a tube of larger or smaller diameter, even though its pitch or taper remains the same.

It is an object of my invention to provide a shaper of novel design which is mounted on its support in such a manner as to permit of adjustments both to regulate the taper of the winding and to accommodate the machine to the winding of cops on tubes of larger or smaller diameters.

It is an object of my invention to provide an improved progression rod, or progression wheel and thread guide carrying rod, which is pivotally supported at one end and adapted to have angular adjustment laterally with respect to the spindle.

It is a further object of my invention to provide adjustable means for regulating the throw of my reciprocating rod in accordance with the taper desired and the diameter of the tubes on which the thread is to be wound.

It is another object of my invention to provide a novel device for regulating the tension on the thread as it is traversed from the small diameter of one end of tapered winding to the large diameter at the other end of the taper.

It is an another object of my invention to provide a novel means on my thread guide carrier for engaging with the shaper and for forcing the laterally adjustable thread guide carrier rod angularly toward the spindle.

Other objects of my invention will appear in the accompanying specification and claims and will be disclosed in the accompanying drawings, in which—

Figure 1 is a side elevation with portions broken away of a portion of a winding machine embodying my invention;

Figure 2 is a plan view of the device as shown in Figure 1;

Figure 3 is a detail in perspective of my shaper;

Figure 4 is an end view of the shaper shown in Figure 3;

Figure 5 is a detail in perspective of a portion of the means for permitting lateral adjustment of the progression rod;

Figure 6 is an end view partly in section of the device shown in Figure 5;

Figure 7 is a side elevation, largely in section, of the device shown in Figure 6; and showing the means for securing my tensioning device to the traverse bar;

Figure 8 is a plan view, in detail, of my tensioning device in operative position;

Figure 9 is a section on the line 9—9 of Figure 8;

Figure 10 is a detail of the friction tensioning device.

Referring now with greater particularity to the drawings it will be seen that my device is comprised as follows:

The usual frame 1, spindle 2 mounted in bearings 3 in the frame and driven through the disk 4, is provided. A clutch and brake mechanism 5 together with a thread guide carrier and progression wheel assembly 6 are also provided as shown.

The traverse bar 7 is slidably mounted in a bearing 8 in the frame 1 and is pivotally secured at 9 to a link 10 which in turn is pivotally secured to a substantially vertically extending curved arm 11 fixedly carried by the usual rock shaft 12. The link 10 may be connected with the arm 11 at any of the apertures 13. This provides for adjustment to vary the throw of the traverse rod. The arm 11 is curved in such a manner that the traverse rod is always moved forward to the same point irrespective of the variation in the length of the throw of the rod. This structure is necessary to permit the proper functioning of the clutch mechanism.

One of a laterally extending cross arm 14 is fixedly secured to the traverse bar 7 for-

wardly of the bearing 8. This cross arm has turned over flanged portions 15 adapted to provide a guideway 16 extending longitudinally of the cross arm and laterally with respect to the spindle. Fixedly secured to the other end of the cross arm 14, by means of a collar 20 and screw 21, is a shaper rod 17 slidably mounted in bearings 18 and 19 in the frame.

10 The guideway 16 is formed to receive and retain the squared plate 22 secured to the end of the progression rod 23 though designed to permit the free movement of the rod therein laterally with respect to the spindle. The progression rod 23 is screw-threaded and is adapted to have screw-threaded engagement with the thread guide carrier assembly which it carries. The forward end of the rod 23 is pivotally secured 15 at 24 to a rod 25 which has a sliding fit in a bearing 26 in the forward end of the arm 27 of the frame.

15 Adjacent the squared plate 22 on the end of the rod 23 a collar 28 is secured by means of a screw 29 extending through the said rod. The end of the screw 29 extends below the collar and a tension spring 30 has one of its ends secured thereto. The other end of the spring 30 is secured to the screw 21. 20 The spring 30 tends to hold the rod 23 and the bar 7 in alignment, or, in other words to hold the rod 23 against the stop 31 in the guideway 16.

25 The detailed structure of my shaper will now be described:

30 The shaper 32 has the shape of a portion of the lateral surface of a frustum of a cone. At the smaller end of the shaper the metal is formed to provide a thin collar 33 having sliding engagement with the shaper rod 17 on which it is mounted. The curvature of the shaper and the rod are essentially concentric at the small end 32^a of the shaper. The base of the shaper is secured by a plate 34 to a collar 35 slidably mounted on the rod 17 and adapted to be fixed in any desired position thereon by means of a set screw 36. The plate 34 is so positioned that the curve of the end 32^b 35 of the shaper is distinctly eccentric of the rod 17. This structure thus permits of adjustment of the shaper 32 both longitudinally of and rotatably about the rod 17.

35 Adjustment of the shaper longitudinally of the rod while maintaining the shaper in its same position rotatively with respect to the rod will not alter the pitch of the taper of the portion of the shaper to be engaged by the finger 37 of the thread guide carrier 40 but will provide for engaging the same earlier or later in the backward movement of the progression wheel depending upon the direction of such adjustment. Adjustment of the shaper inwardly along its rod will 40 permit a greater backward movement of

the progression wheel preparatory to winding. This adjustment will be made for cops or tubes of smaller diameter. Adjustment of the shaper outwardly along its rod will result in an earlier limiting of the backward movement of the progression wheel. This adjustment will be made for tubes and cops of larger diameters.

45 Since one end of the shaper is mounted eccentrically of the shaper rod, it is obvious that rotation of the shaper about the rod will bring surfaces having differing angular positions relating to the spindle into position to be engaged by the finger 37, the taper of least pitch being at 32^a, the surface nearest parallel to the shaper rod and the taper of greatest pitch being at 32^b, the surface at the greatest angle to the rod.

50 It will be noted that I have provided an improved type of contact finger 37. The pressure of the finger against the shaper under the influence of the spring tended to twist the carrier and to bind the same on the rod. In my present device it will be seen that I have pivotally mounted the finger 37^a 55 on the bearing 37^a of the carrier frame 6. The contact end 37^b of the finger 37 has an arcuate face adapted to bear against the surface of the shaper, the arcuate face being an arc of a circle described concentric of the progression rod. The other end 37^c of the finger 37 is bifurcated to straddle the rod 38 of the winding machine.

55 The means for maintaining substantially uniform tension of the thread being wound on the tube will now be described. The necessity for some structure for performing the function of my tensioning device is clearly to be understood when one realizes that the spindle is rotating always at the same speed while the thread guide is being traversed from one end of the tapered winding to the other. Obviously, without a tensioning device, the thread would be comparatively slack when being wound on the small end of the taper and under too great a tension when being wound on the larger end of the taper. Such unevenness of tension would result in irregular and soft-nosed windings.

60 The frame has an upwardly extending arm 40 to which there is secured a device 41, such as is well known in the art, for frictionally, though resiliently, engaging the thread to be wound on the cop or tube to prevent snarling. After leaving the last guide finger of the device 41 the thread passes down to my tensioning device which is comprised as follows:

65 Two guides or fingers 43 and 44, preferably of porcelain or glass, are rigidly secured to arm 40. At a point below the guide 41 and on an extension 45 of the arm 40 there is secured a pin or stub shaft on which a lever 46 is rotatably mounted.

The lever 46 has at one end thereof a laterally extending guide finger 47 which is so positioned that, upon oscillation of the lever about its pivot, the finger 47 is adapted 5 to pass between the fingers 43 and 44. The thread to be wound is fed over fingers 43 and 44 and under the finger 47. The other end of the lever 46 is slotted at 49 to provide a guideway for a pin 48 fixedly connected 10 to the traverse bar 7. Thus it will be seen that the traversing movement of the bar 7 will result in an oscillatory movement of the lever 46 around its pivot. When the lever 7 is in its forward position, that is, when 15 the thread is being wound on the small end of the tapered winding, the finger 47 will move downwardly between the fingers 43 and 44 and take up the slack in the thread. When the bar 7 moves toward the rearward 20 position, that is, when the thread guide carrier moves toward the larger diameter of the winding, the finger 47 will be moved outwardly from between the fingers releasing the tension on the thread and permitting 25 the slack to be taken up in the winding of the larger diameters of the winding. By properly proportioning the arms of the lever 46 and by correctly positioning the fingers 43 and 44 the desired tensioning effect is 30 obtained.

My device having been described in detail its operation will be seen to be as follows: The cop or tube to be used is placed on the spindle and the shaper adjusted longitudinally on its supporting rod in accordance 35 with the diameter thereof. The shaper is then rotated about the shaper rod until the desired taper is reached. The traverse bar link is then adjusted in accordance with the 40 length of throw desired. The thread guide assembly is then moved backward along the progression rod. The finger 37 will then come in contact with the shaper and force the rod 23 against the tension of the spring 45 30 out of alignment with the traverse bar 7, and laterally toward the spindle. This backward movement is continued until the contact wheel almost touches the spindle. The thread is then fed through the thread 50 guide carrier and onto the spindle and the machine is ready for the winding. As the yarn is built up on the spindle, the progression wheel contacts with the same, moving the wheel outwardly along the progression 55 rod and moving the finger 37 outwardly along the surface of the shaper 32 until finally the rod 23 is in alignment with the bar 7 at which point the rear tapered end is completed, the body of the winding being 60 cylindrical from thereon except for the taper of the end which is being wound. The taper of both ends will naturally be of equal pitch though opposite in direction.

When the thread is being wound on the 65 small end of the taper the tensioning device,

as has been described takes up the slack; and when the thread is traversed toward the larger diameters, this slack is gradually released.

I claim:

1. In a winding machine of the character described, a shaper capable of adjustment in a plurality of directions to wind cops on tubes of any of a plurality of diameters.

2. In a winding machine of the character 75 described, a tapered shaper capable of adjustment longitudinally with respect to the traverse rod of said machine for the purpose described.

3. In a winding machine of the character 80 described, a tapered shaper capable of adjustment longitudinally and rotatively with respect to the traverse rod of said machine for the purpose described.

4. In a winding machine, in combination, 85 a traverse bar, a shaper, a member secured to said bar for carrying said shaper at an angle thereto, said shaper being capable of adjustment longitudinally with respect to said bar.

5. In a winding machine, in combination, 90 a traverse bar, an irregularly tapered shaper, a member secured to said bar for carrying said shaper, said shaper being capable of adjustment longitudinally and rotatively with 95 respect to said bar.

6. In combination, in a winding machine 100 of the character described, a traverse bar, a tapered shaper, a member secured to said bar for rotatably and adjustably carrying said shaper, said shaper having one of its ends mounted eccentrically with respect to said member for the purpose described.

7. In combination, in a winding machine 105 of the character described, a traverse bar, a tapered shaper a member secured to said bar for rotatably and adjustably carrying said shaper, said shaper having one of its ends mounted eccentrically with respect to said member for the purpose described, said shaper and said traverse bar being capable 110 of relative adjustment longitudinally with respect to each other.

8. In a winding machine, the combination 115 with a rotating spindle and a thread guide, of means adapted to reciprocate said thread guide longitudinally with respect to said spindle, means engaging the cop on said spindle to feed said guide progressively along said spindle, said means being movable angularly laterally away from said cop to shape the base thereof, a tapered shaper for guiding said means in its movement away from said cop, and means for adjusting said shaper longitudinally with respect 120 to said means.

9. In a winding machine, the combination 125 with a rotating spindle and a thread guide, of means adapted to reciprocate said thread guide longitudinally with respect to said
